UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC COMPANY, A CORPORATION OF ILLINOIS.

TELEPHONE AUTOMATIC TRUNKING APPARATUS.

Application filed January 17, 1907, Serial No. 352,694. Renewed January 28, 1918. Serial No. 214,252.

To all whom it may concern:

Be it known that I, TALBOT G. MARTIN, a citizen of the United States of America, and resident of Chicago, Cook County, Illinois, have invented a certain new and useful Improvement in Telephone Automatic Trunking Apparatus, of which the following is a specification.

My invention relates to telephone exchange systems in general, but more particularly to automatic or semi-automatic systems, and especially to common battery telephone exchange systems in which provision is made for enabling the calling subscribers to automatically trunk between two distant exchanges, or between different divisions of the same exchange.

In my Patent No. 1,185,522, granted May 30, 1916, I have disclosed a combined selector and repeater, and as far as this feature of my present invention is concerned, it is in the nature of an improvement on said previous application. As hereinafter described, I now provide a combined selector and repeater which is adapted for use in trunking in one and the same direction—that is to say, which has the functions of both a selector and a repeater for trunking to another exchange, or to the other division 30 of the same exchange. A herein disclosed embodiment of my present invention comprises, for example, a first-selector which is individual to the calling subscriber's line, which is provided with means for automatically selecting an idle trunk line, and which is further provided with means by which its line relays have the additional function of then acting as repeater relays for controlling one or more automatic switches at the other exchange, or at the other division of the same exchange. In another embodiment of my invention, as herein described and illustrated, I provide second-selectors with which the calling subscribers make connection through the medium of first-selectors or other suitable automatic switches, and which second-selectors are adapted to serve as both selectors and repeaters for automatically trunking to and then controlling the operations of the switches at the other exchange, or at the other division of the same exchange. In these, as well as in other obvious embodiments of my invention, it will be seen that I provide a system and apparatus of such

character that the calling subscriber may transmit electrical impulses for operating an automatic selector switch containing means by which all subsequent impulses transmitted from the calling substation are not employed for directly controlling the switch or switches at the other exchange, or at the other division of the same exchange, but to the contrary are employed for merely actuating a pair of line relays which repeat the impulses and thus directly control the operations of the next or succeeding switch or switches. In other words, I provide an automatic trunk-selecting switch having a pair of line relays adapted to first control the operations of the said switch, and, after the proper selection thereby of an idle trunk line, then repeat to the next or succeeding switch or switches all subsequent electrical impulses transmitted by the calling subscriber. In this way the said line relays have the double function of controlling their allotted switch mechanism and serving as repeater relays for controlling other automatic switches. Furthermore, and as a feature of special improvement, these relays not only have the double function of controlling their allotted selectors and repeating impulses to the subsequent switch or switches, but also have the additional function of serving as resistance and impedance elements for feeding talking current from the battery or other centralized source to the calling subscriber's line for talking purposes—that is to say, for charging the microphone transmitter at the calling subscriber's substation. With these and such other features and combinations as may appear from the following description and accompanying drawings, I find that a considerable saving is accomplished, especially with respect to the cost of installing and maintaining the apparatus, as well as with respect to the primary cost of construction or manufacture.

In the accompanying drawings, Figures 1 and 2 taken together show diagrammatically an established connection between a calling and a called substation, in a system embodying the principles of my invention. The calling substation is shown at A and the called substation at A'. For the broader purposes of my invention, the subscribers may be considered allotted to either the same or different exchanges; but in this case I provide a system and apparatus of such

the substation A, together with its allotted switch (shown in Fig. 1) is considered as belonging to an exchange #1, and the substation A', together with the remaining apparatus, is considered as belonging to the exchange #2. For operating purposes a central current supply source B is provided, having its positive terminal preferably grounded; but sometimes it is desirable to provide a second source B', as in this case where the battery B' is for the exchange #2. Between the said substations is shown the connecting central office switching apparatus, comprising switches characterized by many well-known features. For example: The subscriber's line or individual switch C is an improvement on the selector shown in Patent No. 815,321, granted March 13, 1906, to Keith, Erickson and Erickson. The said switch C, in addition to performing the ordinary functions of the selector, also performs the functions of a repeater, as will be explained. Thus I combine in one switch the features of a selector and a repeater for use in trunking or calling in one and the same direction.

The selector F is a modified form of selector, being used in the system as a second-selector; and the connector D is an improvement on the connector shown in Patent No. 815,176, granted March 13, 1906, to Keith, Erickson and Erickson, being an adaptation of such connector for common battery work. The switch E of the called line is, of course, the same as the switch C of the calling line; and the substations are also, of course, all the same; but where only one battery is used for two or more exchanges a battery lead must of necessity be extended from the battery office to the other central offices. This, however, is usually undesirable in most cases, and one battery is therefore provided for each exchange, as shown in the drawings, where battery B is allotted to exchange #1 and grounded at G, and where battery B' is allotted to exchange #2 and grounded at G'.

Fig. 3 of the drawings shows the switch C used in a different position in the system—that is, after the selector J—and is therefore used as a second-selector. The said selector J is also of the type disclosed in the said selector patent.

Fig. 4 shows the switch C diagrammatically and in perspective.

The substations A and A' may be of any suitable or approved type. The substation A comprises a receiver 2, switch-hook 3, induction-coil 4 which consists of the primary winding 5 and secondary winding 6, transmitter 7, condenser 8, ringer 9, impulse wheel 10 which has the usual vertical impulse teeth 11 that are adapted to operate the vertical impulse spring 12. The impulse wheel carries the rotary impulse tooth 13

which operates the rotary impulse spring 14. The switch-hook has radiating from its body a number of cam arms 15, 16 and 17, and is pivotally secured to the keyboard (not shown) by the screw 18 about which it moves when the receiver is removed. The movement is produced by a spring (not shown), and the switch-hook is pushed up for the purpose of changing certain circuit connections to be disclosed. The cam arm 15 controls the so-called locking arm 19. After the dial is rotated the locking arm 19 occupies the position shown at substation A. The mechanical operations by which this is brought about are well known. The co-operating ground springs 20 and 21 engage, thus placing the ground post 22 in contact with the substation ground G', whereby when the subscriber releases the dial, as described, the vertical impulse teeth 11 will then cause the vertical impulse spring 12 to come into contact with the ground post 22; and immediately following, the rotary impulse tooth 13 causes the rotary impulse spring 14 to come into contact with the same ground post 22. When the switch-hook is down the cam arm 17 maintains a contact between the springs 23 and 24, thereby bridging the condenser 8 in series with the ringer 9 across the line. The springs 25 and 26 are then disengaged, and the primary circuit, including the winding 5 in series with the transmitter 7, is interrupted by the separation of the springs 25 and 26. The signaling device whereby a subscriber may signal another after a connection has been established comprises a push-button 28 and a spring 29, which latter normally engages the contact point 30; but when the push-button 28 is pressed, the spring 29 leaves the contact point 30 and engages the contact point 31 which is connected with the substation ground G'. Means whereby the subscriber may release the central station apparatus brought into service comprises three springs 32, 33 and 34 known as the release springs, and so controlled by the cam arm 16 that when the switch-hook descends the three release springs are brought into contact, thereby grounding both the subscriber's line conductors simultaneously.

The first-selector switch C, shown in Figs. 1, 3 and 4, embodies, among other details, the following well-known devices and circuits: A switch-shaft 38 which carries the vertical and rotary line wipers 39 and 40, respectively, and the private wiper 41. The said wipers are adapted to engage the banks K and L. The side switch M is well known and comprises the side switch wipers 42, 43, 44, 45 and 35 which may be designated as vertical, rotary and private side switch wipers, and the rotary magnet side switch wiper and pole-changer wiper, respectively. The side switch is under the control of the 120

private magnet 46. Through the medium of the vertical line relay 47, and while the side switch is in first position, the subscriber controls the vertical magnet 48, which latter 5 operates to raise the shaft and shaft wipers 39, 40 and 41 vertically. By means of the rotary line relay 49, and while the side switch is in first or second position, the subscriber controls the private magnet 46 10 and, therefore, the side switch. While the side switch is in second position the rotary magnet 50, which carries the shaft and shaft wipers in a rotary or circular direction, is energized. The vertical and rotary line 15 relays 47 and 49, acting conjointly, provide means whereby the subscriber controls the release magnet 51 while the side switch is in first, second or third position. The pole-changing relay 36 is provided for shifting 20 the lead of the rotary line relay 49 from main battery to the ground terminal of the battery when talking battery current is provided by the connector. Furthermore, the shaft 38 is provided with the vertical 25 and longitudinal teeth 52 and 53, respectively, which are adapted to be engaged by the rotary and vertical armature pawls 54 and 55 when their respective magnets become operatively energized. The normal 30 arm 56 controls the springs 57 and 58. The function of the coil spring 59 is to return the shaft 38 to normal position after the said shaft has been released by the operation 35 of the release magnet 51. The lamp 60 is provided for indicating to the switch attendant whether or not the switch is in an operated position. It will be noticed that through the condenser 61 the subscriber's incoming vertical line conductor is transposed to the outgoing rotary line; similarly, 40 through the condenser 62 the subscriber's incoming rotary line conductor is transposed to the outgoing vertical line. The differential relay 63 controls the release magnet circuit, and when the side switch M is in third 45 position the said relay controls the energizing circuit of the pole-changer relay 36.

The second-selector F has the vertical and rotary line relays 64 and 65, but instead of 50 being connected to the battery lead through the bridge-cut-off springs, said relays are connected direct to the battery lead. The bridge-cut-off relay of the said selector patent is omitted in the selector F. The vertical line relay 64 controls the vertical magnet 66, and the rotary line relay 65 controls the private magnet 67, which latter in turn 55 controls the side switch. The two line relays 64 and 65, acting conjointly, provide means whereby the release magnet 68 may 60 become energized. The release relay 69 controls the releasing of the switch after the side switch has passed to third position and established connection with a connector switch. Furthermore, the rotary magnet 70, 65

when the side switch is in second position, operates to give the shaft wipers 71, 72 and 73 a rotary or circular motion.

The connector D is of the type disclosed in my Patent No. 1,332,226, granted March 2, 1920. The vertical and rotary line relays 74 and 75 operate to impart to the shaft wipers 76, 77 and 78 their vertical and rotary motion, respectively. While the side switch is in first position, the vertical line 75 relay 74 controls the vertical magnet 79, and when the side switch passes to second position the rotary magnet 80 comes under the control of the said relay; and similarly, when the side switch is in third position the 80 ringer relay 81 is placed under the control of the vertical line relay 74. The connector rotary line relay 75, as is well known, controls the private magnet 82, which latter in turn operates to shift the side switch wipers 85 83, 84, 85 and 86 from first to second position and from second to third position. The two line relays 74 and 75, acting conjointly, provide means whereby the release magnet 87 may be energized to release the 90 said switch. The differential relay 88 controls the energizing circuit of the back-bridge relay 89, through which latter the called substation receives battery current for talking purposes. Said relay 89, upon en- 95 ergizing, closes a circuit which in turn provides the calling substation with battery current for talking purposes.

The operation of my improved selector switch may be more clearly understood from the step-by-step description of its action in the establishment of a connection. Assume, for example, that the subscriber at substation A, or the line #5000 which terminates in the central office #1, desires to call the 100 subscriber at the substation A' allotted to the line #2200 terminating in central exchange #2. The calling operations by which the connection is brought about are as follows: Upon removing the receiver 2 from the switch-hook 3 and operating the dial for the first digit 2, the vertical and rotary line conductors 90 and 91 are alternately grounded, the former twice and the latter once, upon the return motion of the dial. Grounding the vertical line conductor 90 closes an 105 energizing circuit through the vertical line relay 47 of the selector C, said circuit extending from ground G' through the ground springs 20 and 21, ground post 22, impulse 110 spring 12, conductor 90, conductor 92, vertical line relay 47, winding 93 of the differential relay 63 to the battery lead 94, thence through battery B and to ground G. Each 115 time that the vertical line relay 47 operates, an energizing circuit is established through the vertical magnet 48, extending from ground G' through the springs 95 and 96, conductor 97, side switch wiper 42, contact point 98, through the vertical magnet 48, 120 125

130

conductor 99, private magnet springs 100 and 101, conductor 102, springs 103 and 104 to the battery lead 94, thence through battery B and to ground G. The vertical magnet 48 in turn operates to raise the shaft and shaft wipers 39, 40 and 41 two steps. Following the vertical impulse the rotary line relay 49 becomes energized over a circuit extending from ground G', impulse spring 14, rotary line conductor 91, conductor 105, rotary line relay 49, winding 106 of the differential relay 63, through the springs 103 and 104 to the battery lead 94, thence through battery B and to ground G. The rotary line relay 49, upon operating, presses the springs 95 and 107 into contact, whereby an energizing circuit is closed through the private magnet 46 extending from ground G², springs 95 and 107, conductor 108, side switch wiper 43, contact point 109, conductor 110, private magnet 46 to the battery lead 94, thence through battery B and to ground G. The private magnet, upon operating, releases the side switch M to second position, whereby an energizing circuit is set up through the rotary magnet 50. Said circuit extends from ground G² through the side switch wiper 45, contact point 111, conductor 112, interrupter springs 113', rotary magnet 50 to the battery lead 94, thence through battery B and to ground G. The rotary magnet is energized one step, and the shaft wipers 39, 40 and 41 are carried into engagement with bank contacts that constitute the terminals of a trunk line the conductors of which are similar to the trunk conductors 113 and 114 leading from the tenth set of contacts of the second level, and which conductors 113 and 114 terminate in the switch F at the exchange #2. But if the first trunk line is busy the first private bank contact is, of course, grounded, and an energizing circuit is established through the private magnet 46 when the private wiper 41 strikes the grounded private bank contact, thereby retaining the side switch in second position and maintaining the energizing circuit through the rotary magnet 50. The rotary magnet, by continuing to rotate the wipers, breaks the energizing circuit of the private magnet 46 as soon as an idle trunk line is found, and as soon as the private magnet 46 is de-energized the side switch is tripped into third position; but if there are no busy contacts to be passed over, the rotary magnet 50, as is well known, trips the side switch to third position. If, however, the first nine trunks are busy the shaft will be rotated onto the tenth set of contacts, at which point the private magnet circuit is broken, with the result that the side switch wipers 42, 43, 44, 45 and 35 engage their respective contact points 115, 116, 117, 118 and 119, thus extending the subscriber's line conductors 90 and 91 to the se-

lector F. Also, since the side switch wiper 44 engages the grounded contact point 117, a guarding potential is established at the private wiper 41 for protecting the seized trunk line from being molested by any other switch. Furthermore, on the first vertical step of the shaft the normal arm 56 permits the normal springs 57 and 58 to engage, thereby closing a circuit through the signal lamp 60 as follows: from ground G⁴ through the springs 57 and 58, lamp 60 to the battery lead 94, thence through battery B and to ground G. The lamp, upon glowing, indicates to the switch attendant that the allotted switch is in an operated position. The subscriber, upon grounding the line conductors 90 and 91 for the second digit 2, energizes the vertical and rotary line relays 47 and 49 as before, since the line relays are permanently bridged across the line; but the said relays upon energizing in turn operate to ground the trunk conductors 113 and 114, as will be explained. Now, since the side switch M has passed to third position, the impulses are repeated to the vertical and rotary line relays 64 and 65, respectively, of the selector switch F which is located in the central office #2. The vertical line relay 47 energizes and operates as stated; but when the springs 95 and 96 engage, an energizing circuit is closed through the vertical line relay 64 at the selector F over the following circuit: From ground G², springs 95 and 96, conductor 97, wiper 42, contact point 115, conductor 120, springs 121 and 122, conductor 123, shaft wiper 39, trunk conductor 113, side switch wiper 124, contact point 125, vertical line relay 64 to the battery lead 126, thence through battery B' and to ground G'. The vertical line relay 64 upon energizing places the springs 127 and 128 in contact, thereby closing an energizing circuit through the vertical magnet 66 extending from ground G⁵ through the springs 127 and 128, private springs 129 and 130, vertical magnet 66, thence to battery lead 126, and from battery B' to ground G'. The vertical magnet operates to carry the shaft wipers 71, 72 and 73 two steps opposite the bank level in which are located the terminals of the trunk lines leading to the connector D, Fig. 2. The rotary line relay 49 of the selector C upon energizing places the springs 107 and 95 in contact, whereby an energizing circuit is closed through the rotary line relay 65 of the selector switch F. This circuit extends from ground G² through the springs 95 and 107, conductor 108, side switch wiper 43, contact point 116, conductor 131, springs 132 and 133, conductor 134, shaft wiper 40, rotary trunk conductor 114, side switch wiper 135, contact point 136, rotary line relay 65 to the battery lead 126, thence through battery B' to ground G'. The rotary line relay 65, upon energizing, closes an energizing

circuit through the private magnet 67 extending from ground G^5 through the springs 127 and 137 to the private magnet 67, thence to the battery lead 126, and from battery 5 B' to ground G' . As is well known, the private magnet controls the side switch, which latter now passes to second position, whereby an energizing circuit is closed through the rotary magnet 70 extending 10 from ground G^9 , contact point 138, side switch wiper 139, interrupter springs 140, through the rotary magnet 70 to the battery lead 126, thence through battery B' to ground G' . The rotary magnet, upon operating, rotates the shaft wipers, as is well known, onto an idle trunk line. When the idle trunk line is seized the side switch wipers pass to third position, thus extending 15 the calling subscriber's line conductors 90 and 91 to the conductors 141 and 142 which, it will be assumed, lead to the connector D. Furthermore, when the side switch wiper 143 passes to third position, a guarding potential is established at the private wiper 20 73 (which latter has engaged the conductor 144) for protecting the seized line against being molested by other switches. The effect of grounding the line conductors 90 and 91 for the last two digits (naught and 25 naught) is directed toward the connector D by the selector switch C in the same manner in which the second digit operation was directed toward the selector switch F. Grounding the vertical line conductor 90 ten 30 times for the third digit operates the vertical line relay 47 of the selector switch C ten times, as previously explained; the said relay in turn repeats the ten impulses, grounding the vertical trunk line conductor 113 ten 35 times, which conductor is now extended to the connector vertical line relay 74. The connector vertical line relay 74, therefore, becomes energized over a circuit extending from ground G^2 at the selector C, as explained, to the conductor 113, thence through 40 the side switch wiper 124, contact point 145, conductor 141, vertical line relay 74, through the winding 146 of the differential relay 88 to the battery lead 126, thence through battery 45 B' to ground G' . The relay 88, of course, becomes energized, since the winding 146 is in series with the relay 74; but the energization of the said differential relay at this time is without effect. 50 Each time that the vertical line relay 74 is energized the line relay springs 147 and 148 are pressed into contact, thereby closing an energizing circuit through the vertical magnet 79 over the following path: From ground G^6 to the springs 147 and 148, private magnet springs 149 and 150, side switch wiper 86, contact point 151, vertical magnet 55 79 to the battery lead 126, thence through battery B' to ground G' . The vertical magnet, thus energized, operates to raise the

shaft and shaft wipers one step at a time until the said wipers are carried ten steps to the bank level in which are located the terminals of the line #2200. When the rotary line conductor 91 is grounded the rotary line relay of the switch C is energized, which in turn operates to ground the rotary trunk conductor 114, whereby the connector rotary line relay 75 becomes energized through the following path: from ground G^2 70 to the rotary trunk line conductor 114, as explained, side switch wiper 135, contact point 152, shaft wiper 72, trunk conductor 142, rotary line relay 75, winding 153 of the differential relay 88, springs 154 and 155 to the battery lead 126, thence through battery B' to ground G' . Since the winding 153 of the differential relay 88 is in series with the rotary line relay 75, the differential relay 88 becomes operative, but at 80 this time it is without effect. The energization of the rotary line relay 75 causes the energization of the private magnet 82 over a circuit extending from ground G^6 through the springs 147 and 156 to the private magnet 82, springs 154 and 155 to the battery lead 126, thence through battery B' to ground G' . As a result the side switch is released from first to second position, thus placing the wipers 83, 84, 85 and 86 in connection with the contact points of the second position. The last digit being naught, the subscriber operates the dial, as previously described, grounding the vertical line conductor 90 ten times and the rotary line conductor 91 once. The vertical and rotary line relays 74 and 75 are operated over previously traced circuits. However, when the connector line relay springs 147 and 148 engage, a circuit is closed through the rotary 90 magnet 80 instead of through the vertical magnet 79. The energizing circuit extends from ground G^6 through the springs 147 and 148, private magnet springs 149 and 150, side switch wiper 86, contact point 157, rotary 95 magnet 80 to the battery lead 126, thence through battery B' to ground G' . Each time that the rotary magnet is energized it operates to rotate the shaft and shaft wipers 76, 77 and 78 one step at a time until the 100 said wipers are carried into engagement with the normal conductors 158, 159 and 160, the former two of which lead to the line terminals of the desired subscriber. The energization of the rotary line relay 75, 105 as previously stated, completes an energizing circuit through the private magnet 82 which now operates with one of two results, namely the release of the side switch from second to third position, or the so-called 110 busy release of the connector, which latter operation is brought about in the well-known manner. Assume the former result to occur and the side switch to pass to third position, thus placing the side switch wipers 115

83, 84, 85 and 86 in contact with their respective contact points in third position. Furthermore, when the side switch passes to third position a guarding potential is established for protecting the called line. This potential extends from ground G^7 , contact point 161 to the side switch wiper 85, switch shaft wiper 78, which latter engages the private contact of the called line. The said 10 guarding potential also closes an energizing circuit through the pole-changing and cut-off relay 162 of the selector E. To signal the called subscriber the calling subscriber presses the signaling button 28, placing the 15 contact 29 in contact with the substation ground, thereby energizing the selector vertical line relay 47 and in turn the connector vertical line relay 74. The path of the energizing circuit extends from ground G' through the springs 20 and 21, contact point 31, spring 29, springs 26 and 25 to the vertical line conductor 90, thus energizing the selector vertical line relay 47, as explained. The said relay repeats the impulse from 20 ground G^2 to the conductor 113, side switch wiper 124, contact point 145, shaft wiper 71, conductor 141, through the vertical line relay 74, winding 146 of the differential relay 88 to the battery lead 126, thence 25 through battery B' and to ground G' . It will be remembered that the connector side switch has passed from second to third position, and that the side switch wiper 86 is in engagement with the contact point 163, thereby placing the vertical line relay 74 in control of the ringer relay 81 in the same manner in which the rotary magnet 80 came under the control of the vertical line relay when the side switch passed from first to 30 second position. Therefore, when the vertical line relay presses the springs 147 and 148 into contact, the ringer relay 81 is energized by a flow of current from ground G^6 through the springs 147 and 148, private magnet springs 149 and 150, side switch wiper 86, contact point 163, ringer relay 81, springs 164 and 165 (bearing in mind that the differential relay 88 is energized) to the battery lead 126, thence through battery 35 B' to ground G' . The ringer relay, upon energizing, shifts the spring 166 out of contact with the spring 167 and into engagement with the spring 168, and the spring 169 is shifted into engagement with the spring 50 170. This results in bridging the terminals of the ringer generator H across the called subscriber's line. A signaling current is therefore sent from the generator H to the ringer relay springs 170 and 169, side switch wiper 83, contact point 171, shaft wiper 76, normal conductor 158, vertical line conductor 172, condenser 173, ringer 174, springs 175 and 176 to the rotary line conductor 177, rotary normal conductor 159, shaft wiper 77, contact point 178, side switch wiper 84,

ringer relay springs 166 and 168 back to the generator H. As soon as the calling subscriber ceases to press the signaling button 28 the ringer relay 81 becomes de-energized and the springs 166 and 169 resume their 70 normal positions. The subscriber at substation #2200, in response to the signal, removes the receiver 179 from the switch-hook 180, which allows the springs 181' and 182' to engage, and the springs 175 and 176 to disengage, thereby removing the ringer 174 from across his line. The engagement of the springs 181' and 182' closes a series energizing circuit through both windings of the relay 89 at the connector D, said circuit extending from ground G^7 to the contact point 161, side switch wiper 85, winding 181 of the relay 89, through the ringer springs 167 and 166, side switch wiper 84, contact point 178, shaft wiper 77, rotary normal conductor 159, rotary line conductor 177, primary winding 182, transmitter 183, through the signaling device of the called substation, through the springs 181' and 182', vertical line conductor 172, normal conductor 158, shaft wiper 76, contact point 171, wiper 83, through the winding 184 of the relay 89, springs 185 and 165 to the battery lead 126, thence through battery B' and to ground G' . The relay 89, upon energizing, operates to shift the spring 154 from the spring 155 (which latter is connected to the battery lead 126) to the spring 186, which is in turn connected with ground. This reversal of the polarity of the spring 154 sets up a circuit which energizes the pole-changing relay 36 of the selector C. This circuit may be traced from ground G^7 to the contact point 161, side switch wiper 85, through the springs 186 and 154, winding 153 of the differential relay 88, rotary line relay 75, conductor 142, shaft wiper 72, side switch wiper 135, rotary trunk line conductor 114, shaft wiper 40, conductor 134 (Fig. 4), springs 186' and 187, contact point 119, side switch wiper 35, conductor 188, through the pole-changing relay 36, conductor 123 to the vertical line shaft wiper 39, vertical trunk conductor 113, side switch wiper 124, contact point 145, shaft wiper 71, conductor 141, vertical line relay 74, winding 146 of the differential relay 88 to the battery lead 126, thence through battery B' and to ground G' . The relay 36 upon energizing, operates to disengage the springs 121 and 122 and springs 132 and 133, and to shift the spring 103 out of contact with the spring 104 (which latter is connected with the battery lead 94) into engagement with the spring 189 which is in turn connected to ground. This operation of the relay 36 closes a circuit which provides the calling subscriber with battery current for talking purposes. The said circuit extends from ground G^8 through the side switch wiper 45, contact 130

- point 118, conductor 190, springs 189 and 103, through the winding 106 of the differential relay 63, rotary line relay 49, conductor 105, rotary line conductor 91, primary winding 5, transmitter 7, springs 26 and 25, vertical line conductor 90, conductor 92, vertical line relay 47, winding 93 of the differential relay 63 to the battery lead 94, thence through battery B and to ground G.
- 10 The two substations being thus provided with battery current for talking purposes, communication may now be carried on over the circuit shown by the heavy lines in Figs. 1 and 2.
- 15 The release of the switching apparatus is brought about when the calling subscriber restores the receiver 2 to the switch-hook 3, thereby pressing the release springs 32, 33 and 34 into engagement for a moment. The 20 contact of the said release springs grounds the vertical and rotary line conductors 90 and 91 simultaneously from ground G' to the release spring 32, thence through the springs 33 and 34 to the rotary and vertical line conductors. The grounding of the rotary line conductor 91 produces a short-circuiting or shunting of the rotary line relay 49 in series with the winding 106 of the differential relay 63, extending from ground 25 G' to the side switch wiper 45, contact point 118, springs 189 and 103, winding 106 of the differential relay 63, rotary line relay 49 to the rotary line conductor 91, to the release springs 33 and 32 to ground G'. Therefore, 30 since the winding 93 of the differential relay 63 alone carries current, the said relay becomes energized and attracts its armature, which shifts the spring 187 out of contact with the spring 186', and places the springs 35 191 and 192 in engagement. The disengagement of the springs 186' and 187 destroys the energizing circuit through the relay 36, and the spring 103 passes out of engagement with the spring 189 and into contact with the spring 104, which removes the said short-circuit from the rotary relay 49 and winding 106, establishing an energizing circuit instead extending from the substation ground G' through the release springs 32 40 and 33 to the rotary line conductor 91, relay 49, winding 106 of the differential relay 63, through the springs 103 and 104 to the battery lead 94, thence through battery B and to ground G. The rotary relay 49 now 45 operates and the springs 193 and 194 come into contact, whereby an energizing circuit is established through the release magnet 51 of the selector C. However, the current now in passing through the winding 106, as above 50 stated, aids the winding 93 in maintaining the springs 191 and 192 in contact. The energizing circuit through the release magnet 51 extends from ground G' to the springs 193 and 194, release magnet 51, springs 191 and 192 to the battery lead 94, and through 55 battery B to ground G. The release magnet energizes and remains in readiness to release the selector switch when the energizing circuit is broken. Both the vertical and rotary line relays 47 and 49 being energized simultaneously, the trunk line conductors 113 and 114 leading to the sub-central station become grounded simultaneously over circuits previously pointed out. The grounding of the rotary trunk conductor 114 produces a 60 short-circuit of the rotary line relay 75 in series with the winding 153 of the differential relay 88 extending from ground G' to the contact point 161, side switch wiper 85, springs 186 and 154, winding 153 of the differential relay 88, rotary line relay 75 to the rotary trunk conductor 142, shaft wiper 72, wiper 135, rotary trunk conductor 114 and to ground G'. Therefore, since the winding 146 of the differential relay 88 alone 65 carries current the said relay becomes energized and attracts its armature, which shifts the spring 165 out of contact with the spring 185 and into contact with the spring 164. The disengagement of the springs 165 and 70 185 destroys the energizing circuit through the relay 89, and the spring 154 passes out of engagement with the spring 186 and into contact with the spring 155, which removes the said short-circuit from the rotary relay 75 and winding 153, and establishes an energizing circuit instead extending from ground G' at the selector C to the battery lead 126 and then to ground G', as explained. The rotary relay 75 now operates and the springs 75 195 and 196 come into contact, whereby an energizing circuit is established through the release relay 69 of the selector F in series with the release magnet 87 of the connector D. However, since the relay 88 is differentially wound, the current now passing through the winding 153 aids the winding 146 in maintaining the springs 164 and 165 in contact. The energizing circuit through the release relay 69 and the release magnet 87 80 extends from ground G' to the contact point 197, side switch wiper 143, release relay 69, shaft wiper 73, conductor 144, springs 195 and 196, release magnet 87, springs 164 and 165 to the battery lead 126, thence 85 through battery B' and to ground G'. When the connector release magnet 87 is thus supplied with current it energizes, and as a result the switch-shaft and side switch are restored to normal position, thus breaking the connection between the connector switch-shaft wipers 76, 77 and 78 and the normal conductors 158, 159 and 160. The back-release relay 69 of the selector F being 90 in the same circuit with the release magnet 87 energizes simultaneously with the latter, and operates to close a circuit through the selector release magnet 68 by pressing the back-release springs 198 and 199 together. The circuit through the said release magnet 68 95 100 105 110 115 120 125 130

extends from ground G¹⁰ through the springs 198 and 199 to the release magnet 68, thence to the battery lead 126 and through battery B' to ground G'. When the ground to the line conductors 90 and 91 is interrupted all the magnets involved in the release are de-energized and all the switches are fully restored. It will be understood, of course, that when the connector switch D is released and the wipers 76 and 77 disengage from the normal conductors 158 and 159, the back-bridge relay 89 of the connector D is restored and the spring 154 controlled by said relay returns into normal engagement with the non-grounded battery spring 155, thus cutting off talking battery current from the calling line. If the called line #2200 is busy at the time that the calling subscriber #5000 attempts to establish connection, the connector D is released by the last impulse to the rotary trunk conductor 114 as follows: The said impulse energizes the rotary line relay 75 of the connector D, which relay in turn energizes the private magnet 82, pressing the private springs 200 and 201 into contact after the private wiper 78 has been carried onto the grounded private bank contact. Of course, it is understood that whenever a line is busy the connector private bank contacts connected with the private normal 160, shown at the selector E, are all connected to ground. Therefore, since the connector side switch is in second position, when the private springs 200 and 201 are brought into contact an energizing circuit is established through the release magnet 87 from the said grounded private bank contact to the private wiper 78, thence to the side switch wiper 85 (which is in second position), to the private magnet springs 200 and 201, to the release magnet 87, springs 164 and 165 to the battery lead 126, thence to battery B' and to ground G'. The connector switch-shaft and side switch are thus released in the manner disclosed in the said connector patent, and connection is not established with the called line, nor is there any liability of the back-bridge relay 89 energizing, thus making it impossible for the calling line to receive talking battery current. The busy signal is established when the subscriber presses his signaling button 28, after he has completed the calling operations, and, of course, after the connector is released, as described. The connector side switch being in first position, as explained, when the vertical line conductor is grounded by pressing the signaling button spring 29 onto the ground contact 31, the connector vertical line relay 74 is then energized as before. Therefore, the line relay springs 147 and 148 are brought into contact, and the vertical magnet 79 is operated to raise the switch-shaft, whereby the off-normal springs 202 and 203 are brought into con-

tact and a busy signaling current is sent to the calling substation from the busy coil I through the springs 203 and 202 to the side switch wiper 84, ringer relay springs 166 and 167, condenser 218 to the rotary trunk conductor 114, condenser 61 of the switch C to the vertical line conductor 90, thence through the primary winding 5 to the rotary line conductor 91, and through the condenser 62 of the switch C to the vertical trunk conductor 113, line relay 74 of the connector D, and winding 146 of the differential relay 88 to the battery lead 126, and to the busy coil I. When the subscriber hangs up his receiver after receiving the busy signal, he grounds the line conductors 90 and 91 simultaneously, energizing the line relays of the selector C and connector D simultaneously, as already explained, thus producing the release of the switching apparatus as follows:

As soon as the vertical and rotary line conductors 90 and 91 are grounded, the vertical and rotary line relays 47 and 49 and the differential relay 63 of the switch C are energized, whereby the line relay springs 193 and 194 are brought into contact at the same time that the differential relay springs 191 and 192 are brought into contact; thus an energizing circuit is established through the release magnet 51 over circuits that have already been pointed out. At the same time the line relay springs 96 and 107 are, of course, carried onto the ground spring 95, and as a result the trunk conductors 113 and 114 are grounded simultaneously, whereby the vertical and rotary line relays 74 and 75 and the differential relay 88 are energized simultaneously, causing the release magnet 82 of the connector D and the back-release relay 69 of the switch F to be energized simultaneously. As a result of the energizing of the said release magnet the connector is released, as already explained; but the remaining release circuits and mechanisms are retained in readiness to perform the final release operations as soon as the ground circuits are removed from the line conductors, at which time a release of all switches follows in the manner already explained. The selector C, in addition to establishing connection in a distant sub-central, may also be used in establishing connections in the local central office; that is, the subscriber at substation A may call other subscribers whose telephone lines terminate in the same office. In that event the shaft wipers 39, 40 and 41 are raised and rotated into engagement with contacts of those bank levels in which conductors lead to selector switches located in the same office, one of which is diagrammatically shown at N in Fig. 1. I do not confine my improved selector switch C to the exact location in a central office shown

in Figs. 1 and 2; for as shown in Fig. 3 the calling substation A may have allotted thereto a selector switch J of the type disclosed in said selector patent, and the selector C may be employed as the second switch on the line from which the impulses delivered to the selector switch C are repeated (as explained) to the next switch, which latter may be in a distant sub-central exchange, or may be in the same local office as the selector C. It will be understood that when the selector switch C is used in this manner the normal conductors 204, 205 and 206, shown in Fig. 1, leading to the selector C then lead to the selector J, Fig. 3, since the latter is allotted to the line #5000, and the selectors C are employed on a percentage basis—that is, to a group of one hundred first selectors there may be allotted a group 20 of ten selector switches C; and, also, the trunk-release spring 193 which was formerly connected to ground then leads to the private wiper bank of the switch J and to other banks in multiple. As shown in Fig. 25 3, the selector switch J comprises the vertical and rotary line relays 207 and 208 which receive battery current through the springs of the bridge-cut-off relay 209. The said line relays are adapted to operate the 30 vertical magnet 210, private magnet 211, and both relays acting conjointly provide means whereby the calling subscriber may energize the release magnet 212 while the side switch wipers are in first or second position. As is well known, the rotary magnet 213 imparts to the shaft wipers 214, 215 and 216 their rotary or circular motion. The release relay 217 provides means whereby the selector may be released after connection has been established by way of the shaft wipers 214 and 215 with the next switch. As shown in said Fig. 3, the selector J has established connection with the selector C, and the selector C has in turn 45 seized a trunk line which may lead to another central office. Furthermore, the selector switch may be operated to engage trunk lines which lead to other selector switches N, said selector switches being similar to the selectors F or C. Similarly, the switch C is not confined to the function of establishing distant trunking connections, but is adapted to perform the usual functions of selector switches. It will be 55 noticed by comparing selector J with selector F that another modification or special feature in the said switch F consists in the provision of two line relay release springs 219 and 220, so that if it becomes necessary 60 to release a connection before the side switch of the said switch F passes to third position the release magnet 68 will be energized directly by the operating of the line relays 64 and 65, which relays upon 65 thus operating press the said springs 219

and 220 into contact, establishing a circuit through the release magnet 68 from ground G⁵ through the said springs 219 and 220, and through the release magnet to battery.

The various relays may be of any suitable 70 resistance, but good results have been obtained when the vertical and rotary line relays 47 and 49 are wound to a resistance of five hundred ohms each; the relay 36 to a resistance of five hundred ohms; and the 75 windings of the differential relay 63 to a resistance of two hundred and fifty ohms each.

In either embodiment of my invention therefore, as shown in Figs. 1 and 3, I provide a pair of line relays which are individual to a line running thereto, which are adapted for controlling the operations of their allotted selector mechanism, which are adapted to act as repeater relays for controlling the operations of the subsequent switch or switches, and which also serve as resistance or impedance elements for feeding talking current from the battery or other centralized source to the calling subscriber's 80 line to charge the microphone transmitter thereof. It will be seen, of course, that these relays also have more or less to do with the releasing of their allotted selector mechanism, in the manner explained. With 85 such arrangement a pole-changing relay is provided for the calling subscriber, as, for example, in a combined selector and repeater, and another pole-changing relay is provided for the called subscriber, as, for 90 example, in the common battery connector. The current for charging the calling subscriber's microphone transmitter is received through the line relays of a selector switch, while the current for charging the called 95 subscriber's microphone transmitter is received through the windings of a connector relay. Thus the combined selector and repeater C is adapted for the double function of selectively trunking and repeating in one 100 and the same direction, and is adapted for controlling and regulating the flow of talking current to the calling subscriber, regardless of whether it is employed in the position shown in Fig. 1, or in the manner 105 shown in Fig. 3. In either case, as explained, it will be seen that the called subscriber controls the operations by which the battery is switched into the bridge between the two line relays of the said selector and 110 repeater C to supply talking current to the calling subscriber. The trunk-selecting and impulse-repeating functions of the switching machine C are, however, controlled by the calling subscriber before the called subscriber answers. 115

What I claim as my invention is:—

1. In a telephone exchange system, the combination of a trunk line, an automatic switch in which said trunk line terminates, 130

an automatic switch mechanism for connecting with the other end of said trunk line, a line relay allotted to and controlling said mechanism, another line relay allotted to 5 and controlling the said automatic switch, a circuit by which the first relay controls the second relay over the trunk line, a circuit for energizing the first relay to cause the said switch mechanism and automatic switch 10 to be controlled successively thereby, a motor magnet for said mechanism, a circuit for said magnet extending through contacts of said first relay, and means for operating said automatic switches by a varying number 15 of impulses.

2. In a telephone exchange system, the combination of a calling telephone line, an automatic switch, an idle trunk line leading to said switch, a selector switch mechanism 20 for extending connection from the calling telephone line to the said idle trunk line, a pair of line relays for controlling said selector switch mechanism and adapted to control the operations thereof, means by which 25 the calling subscriber also employs said relays for controlling the operations of the said automatic switch, means for feeding talking current through the windings of said relays to the calling subscriber's substation, 30 a motor magnet for said mechanism, and a circuit for said magnet extending through contacts of one of said relays.

3. In a telephone exchange system, the combination of an idle trunk line, an automatic selector switch mechanism for making connection with said trunk line, a pair 35 of line relays for controlling said selector switch mechanism, an automatic switch responsive to said relays and forming the terminal of the other end of said idle trunk line, means for causing said pair of relays to successively control the said switch mechanism and automatic switch, means for feeding talking current through the windings of said relays to the calling subscriber's substation, a motor magnet for said mechanism, and a circuit for said magnet extending through contacts of one of said relays. 45

4. In a telephone exchange system, the combination of trunk lines, an automatic trunk-selecting switch for extending connection over any one of said trunk lines, a pair of relays for controlling said trunk-selecting switch, an automatic switch at the 55 other end of each trunk line, each automatic switch being responsive to said relays after connection is made with the trunk line allotted to such switch, a calling subscriber's impulse-transmitting device by which said relays are caused to successively control the 60 said trunk-selecting switch and an idle one of said automatic switches, means for feeding talking current through the windings of said relays to the calling subscriber's substation, a motor magnet for said first switch 65

and a circuit for said magnet extending through contacts of one of said relays.

5. In a telephone exchange system, the combination of an automatic switch mechanism, a pair of line relays allotted to said 70 mechanism, local operating circuits for said mechanism directly controlled by said relays, an automatic switch also controlled by said relays, a calling telephone line, a called telephone line, and suitable instrumentalities for supplying talking current through the windings of said relays to the calling subscriber's line, and through the said automatic switch to the called subscriber's line. 75

6. An automatic selector switch provided with a pair of line wipers, a pair of crossed or transposed line conductors permanently connected to said wipers, means including a relay for causing a step-by-step operation of said wipers; trunk line terminals adapted 80 to be engaged by said wipers, automatic means for preventing the wipers from engaging the terminals of busy trunks, magnets by which a subscriber operates the said switch, circuits for said magnets independent 85 of said line conductors, and switches at the end of said trunk lines adapted to be controlled by the said first relay. 90

7. The combination of a line, a plurality of trunks, a trunk selector in which said line terminates, automatic switches in which the said trunks terminate, a pair of line relays associated with the said trunk selector and adapted to control the trunk-selecting operations thereof, and means by which said relays are caused to repeat switch-operating impulses from said line to an idle trunk after a selection of the latter is made, a motor magnet for said trunk selector, and a circuit for said magnet independent of said line and trunk extending through contacts of one of said relays. 95

8. The combination of a subscriber's line, a suitable trunk, switching means individual to said line for connecting with said trunk, a second switching means responsive to said first switching means and located at the end of said trunk, means for using said first switching means to operate the second switching means after the line and the trunk are joined together, means in said switching means to supply current for talking purposes, a motor magnet for said first switching means, and a circuit for said magnet directly controlled by said last means. 110

9. In a telephone exchange system, the combination of a calling telephone line, a called telephone line, means including a selector switch and a connector switch for joining the two lines together, a pair of line relays for the selector for controlling the operation of said selector to extend a connection, a pair of resistance windings for the connector, two common batteries or centralized sources of current supply, means for 115 120 125 130

- switching one battery in series between the two windings of the selector relays to supply current to the calling telephone line, and means for including the other battery 5 in series between the resistance windings of the connector to supply talking current to the called telephone line.
10. In a telephone exchange system, a pair of condensers, a line having the two sides 10 thereof terminating in said condensers, a pair of line wipers, trunk line terminals for said wipers, a pair of crossed conductors connecting said condensers with said line wipers, a pair of relays bridged across the 15 said line, means for transmitting impulses over the line to operate said relays, means controlled by said relays for operating said wipers, and switches at the end of said trunk lines adapted to be controlled by the 20 said relays.
11. In a telephone exchange system, the combination of a selector provided with a pair of line wipers and a pair of line conductors suitably connected therewith, a pole-changing relay bridged across the said line wipers, a pair of line relays bridged across the said line conductors, a battery having one pole normally connected between said line relays, a trunk line having a terminal 25 temporarily engaged by said line wipers, means operated by the energizing of said pole-changing relay for switching the battery in series between the two line relays, and means for supplying current over the 30 said trunk line and through the said wipers to energize said pole-changing relay.
12. In a telephone exchange system, the combination of a selector provided with a pair of line wipers and a pair of line conductors suitably connected therewith, a pole-changing relay bridged across the said line wipers, a pair of line relays bridged across the said line conductors, a battery having one pole normally connected between said line 35 relays, a trunk line having a terminal temporarily engaged by said line wipers, means operated by the energizing of said pole-changing relay for switching the battery in series between the two line relays, means for 40 supplying current over the said trunk line and through the said wipers to energize said pole-changing relay, and means by which a called subscriber controls the energizing of said pole-changing relay.
55. 13. An automatic selector switch comprising a pair of line wipers, a pole-changing relay bridged across the said line wipers, a pair of line conductors suitably connected with said line wipers, a pair of line relays 60 bridged across said line conductors, a battery having one pole normally connected between said line relays, a differential relay having two windings each of which is connected in series with one of the line relays, an energizing circuit for the pole-changing relay con-
- trolled by said differential relay, means operated by the energizing of the pole-changing relay for switching the battery in series between the windings of the differential relay and the line relays, a trunk line temporarily seized by said line wipers, a source of energizing current, and means for connecting said source of current with the other end of said trunk line to supply current back through the said wipers and through the winding of the pole-changing relay to 70 operatively energize the latter.
14. In a telephone exchange system, the combination of a calling telephone line, a called telephone line, a selector switch provided with crossed or transposed line conductors, a connector switch by which the called telephone line is temporarily seized, suitable trunk line connection between the two switches, relay means in the selector for 75 controlling its own operations as well as the operations of the connector switch, and suitable instrumentalities for supplying talking current through the said relay means of the selector switch to the calling telephone line, and through the connector switch to the called telephone line.
15. In a telephone system, a subscriber's line, a plurality of trunk lines, a selector switch individual to said subscriber's line 80 for selecting an idle one of said trunk lines, and means in said selector switch for repeating impulses over said trunks.
16. In a telephone system, a plurality of subscribers' lines, a connector switch for 85 connecting with a called line, a switch individual to said called line, and a pole-changing relay in said individual switch adapted to be energized when said connector connects with the called line.
17. In a telephone system, a subscriber's line, an automatic switch individual thereto, a pair of line relays bridged across said line for controlling the operation of said switch, and a differential relay having a 90 winding connected in series with each of said line relays for controlling the release of said switch.
18. In a telephone system, a calling and a called subscriber's line, means including a selector switch operative in accordance with the first digit of the called number for extending the connection from a calling to a called line, a pair of line relays for said selector, a pole-changing relay for said selector, and means for energizing said relay when the called subscriber answers for providing talking current to the calling subscriber's line through said line relays.
19. In a telephone system, a plurality of 95 subscribers' lines, means including a selector switch allotted to each of said lines operative in accordance with the first digit of the called number in establishing a talking circuit between a calling and a called sub-

scriber, relays in each of said switches for supplying talking current to the talking circuit, a motor magnet for each of said switches, and a circuit for each of said magnets extending through contacts of one of the associated relays.

20. In a telephone system, a plurality of subscribers' lines, means including first selectors and second selectors for establishing a talking circuit between a calling and a called line, relays for controlling said second selector, means for supplying talking current to said talking circuit through said relays, a motor magnet for said second selector, and a circuit for said magnet extending through contacts of one of said relays.

21. In a telephone system, a calling and a called line, an automatic connector switch for connecting with a called line, a plurality of switches for extending connection from a calling line to said connector to thereby establish a talking circuit between a calling and a called line, relays for controlling one of said switches, means for supplying talking current to said talking circuit through said relays, a motor magnet for said switch, and a circuit for said magnet extending through contacts of one of said relays.

22. In a telephone system, a plurality of subscribers' lines, means including a selector switch having line relays operative in accordance with the first digit of the called number for establishing a talking connection between a calling and a called line, and means for supplying talking current to the line through said relays when the called subscriber answers.

23. In a telephone system, a subscriber's line, a combined selector and repeater provided with a vertical line relay connected to battery at one side and permanently connected direct to the subscriber's line at the other side, a rotary line relay connected to battery at one side and to the subscriber's line at the other side, a trunk line adapted to be seized by said selector and repeater, and means controlled by said relays for controlling the operation of said combined switch and for repeating impulses over the seized trunk.

24. In a telephone system, a combined first-selector and repeater provided with progressively movable step-by-step side switch wipers and line relay springs, said wipers permanently connected directly to the line relay springs, respectively, and switching means responsive to the same when used as a repeater.

25. In a telephone system in which the subscribers are divided into groups, means having one motion to select groups and another motion to connect with the called line found in the selected group, a combined first-selector and repeater provided with progressively movable step-by-step side

switch wipers permanently connected directly to the line relay springs, respectively, and switching means responsive to the same when used as a repeater.

26. In a telephone system in which the subscribers are divided into groups, means having one motion to select groups and another motion to connect with the called line found in the selected group, a combined selector and repeater for each subscriber, other switches whereby any subscriber may obtain connection with any other subscriber, a pair of condensers in opposite sides of the talking circuit, each said combined selector and repeater including a pair of line shaft wipers permanently connected with the subscriber's line through said condensers.

27. In an automatic telephone exchange trunking system divided into groups, a subscriber's line, a combined selector and repeater provided with a vertical line relay connected to battery at one side permanently connected to the subscriber's line at the other side, a rotary line relay connected to battery at one side and permanently to the subscriber's line at the other side, said selector having one motion to select groups and another motion to automatically select an idle trunk in the selected group and means controlled by said relays for then repeating impulses over the seized trunk.

28. In an automatic telephone exchange trunking system divided into groups, a combined first-selector and repeater provided with side switch wipers, and line relay springs, said wipers permanently connected directly to the line relay springs, respectively, and switching means responsive to the same when used as a repeater, said selector having one motion to select groups and another motion to automatically select an idle trunk in the selected group.

29. In an automatic telephone exchange trunking system divided into groups, a combined selector and repeater for each subscriber, other switches whereby any subscriber may obtain connection with any other subscriber, a pair of condensers in opposite sides of the talking circuit, each said combined selector and repeater including a pair of line shaft wipers permanently connected with the subscriber's line through said condensers, said selector having one motion to select groups and another motion to automatically select an idle trunk in the selected group, as set forth.

30. A telephone system, means for establishing a talking circuit, comprising trunk lines, an automatic trunk selector, a connector having vertical motion to select groups and rotary motion to connect with a line in the selected group, a called subscriber's telephone line adapted to be seized by said connector, a calling subscriber's telephone line, a relay individual to the calling

line to which the selector and connector are successively responsive, said selector responsive to said relay via circuits excluded from said talking circuit, said relay associated with and included in said selector.

31. In a telephone system, a calling telephone line, a called telephone line, means including an automatic trunk selector for extending a talking circuit to the called telephone line, having vertical motion to select groups and rotary motion to connect with a line in the selected group, said selector having a controlling relay permanently connected to the talking circuit and operating magnets controlled over circuits excluding said talking circuit, a source of talking current, and means in said selector responsive to the called subscriber for feeding talking current to the calling line.
32. A telephone system, means for establishing a talking circuit comprising a trunk having an automatic switch at one end thereof, responsive to calling impulses sent over said trunk, and a combined trunk selector and repeater mechanism for seizing the other end of said trunk, when the latter is idle, having means for transmitting the said calling impulses to operate the said automatic switch, said mechanism comprising a relay permanently connected to the talking circuit and operating magnets controlled over circuits excluding said talking circuit.

33. In a trunking system in which the trunks are in groups, means for establishing a talking circuit comprising a trunk line, an automatic switch including a pair of line relays to which the said trunk line leads, a second pair of line relays connected to said talking circuit, means associated with said second relays and controlled thereby over circuits excluding said talking circuit for extending connection to said trunk line, electromagnetic means for said switch, and means by which a calling subscriber controls the energizing of said electromagnetic means through the medium of said second relays, said switch having vertical motion to select groups and rotary motion to connect with the desired line in any predetermined group.

34. In a trunking system in which the trunks are in groups, means for establishing a talking circuit comprising trunk lines, an automatic trunk selector, a connector, a called subscriber's telephone line adapted to be seized by said connector, a calling subscriber's telephone line, a relay individual to the calling line to which the selector and connector are successively responsive, said selector having magnets controlled by said relay over circuits excluding the talking circuit, said relay associated with and included in said selector, said selector having vertical motion to select groups and rotary

motion to automatically select an idle trunk in any predetermined group.

35. A telephone system, means for establishing a talking circuit comprising trunk lines, an automatic trunk selector, an automatic switch for each trunk line, said trunk selector including a pair of line relays, and an automatic progressively movable step-by-step auxiliary switch to enable said relays to control the connector after the selector has been operated, the relays controlling the selector over circuits excluding the said talking circuit.

36. In a telephone system, a calling telephone line, a called telephone line, trunk lines common to said lines, a battery, an impulse sender in the calling line, an automatic trunk selector for selecting an idle one of said trunk lines to extend a talking circuit toward the called telephone line, operating magnets for said selector, a magnet controlling relay in said selector, circuits for controlling said magnets excluding the talking circuit, a source of talking current, and a progressively movable step-by-step electro-magnetically controlled switch and a relay in said selector responsive to the called subscriber for feeding talking current to the calling line.

37. A telephone system including a calling telephone line, directive switching means at the substation thereof, a directly controlled step-by-step selector connected with said line, operating relays for said selector responsive to said means, driving magnets for adjusting said selector responsive to said relays, a trunk circuit including a pair of individual trunk conductors only, multiple contacts at one end of said circuit at said selector and selectable thereby when said circuit is idle, trunk relays connected with said conductors at the other end of said circuit, armature switch mechanism of the relays of said selector conductively connected with said last-mentioned relays on selection made of said circuit, whereby the relays of said selector, operating responsive to said substation means, directly control said trunk relays, and a trunk selector for said circuit at said other end having operating electromagnets controllable by said trunk relays.

38. A telephone system including a calling telephone line, directive switching means at the substation thereof, a selector connected with said line, operating relays for said selector responsive to said means, magnets for adjusting said selector responsive to said relays, a trunk circuit including a pair of individual trunk conductors only, multiple contacts at one end of said circuit at said selector and selectable thereby when said circuit is idle, trunk relays connected with said conductors at the other end of said circuit, armature switch mechanism of the relays of

said selector conductively connected with said last-mentioned relays on selection made of said circuit, whereby the relays of said selector, operating responsive to said substation means, directly control said trunk relays, a trunk selector for said circuit at said other end having operating electromagnets controllable by said trunk relays, release mechanism for restoring said last-mentioned selector, and relay apparatus individual to said first-mentioned selector for rendering said mechanism effective by current changes produced in said individual trunk conductors.

15 39. A telephone system including a calling telephone line, directive switching means at the substation thereof, a selector connected with said line, operating relays for said selector responsive to said means, magnets for adjusting said selector responsive to said relays, a trunk circuit including a pair of individual trunk conductors only, multiple contacts at one end of said circuit at said selector and selectable thereby when said circuit is idle, trunk relays connected with said conductors at the other end of said circuit, armature switch mechanism of the relays of said selector conductively connected with said last-mentioned relays on selection made 30 of said circuit, whereby the relays of said selector, operating responsive to said substation means, directly control said trunk relays, a trunk selector for said circuit at said other end having operating electromagnets 35 controllable by said trunk relays, means for simultaneously energizing said trunk relays responsive to current impulses transmitted over said conductors by said selector relays when disconnection is desired, and a release 40 circuit of said trunk selector operated responsive to the simultaneous energization of said trunk relays.

40 40. A telephone system including a calling line, a directly controlled step-by-step 45 selector at the exchange having operating re-

lays connected with, and responsive to directive currents over said line, traveling contact-makers for said selector, a link-circuit having two individual conductors only for conductive connection to the contact-makers 50 of said selector, said conductors being selectable by said selector responsive to said relays, link-circuit relays conductively connected with said conductors and operable responsive to currents transmitted by said operating relays on selection made, a selective switch for said link-circuit having driving magnets connected with armature switches of said link-circuit relays and operable thereby, and a release circuit for said switch responsive 60 to current changes produced at said selector in said individual conductors to release said selective switch when disconnection is desired.

41. In telephony, a trunk circuit for automatic telephone systems including a pair of trunk conductors only, multiple terminals of said conductors, a directly controlled step-by-step selector at a first exchange for selecting said terminals, driving magnets for 70 said selector and operating relays for controlling the same, trunk relays for said trunk circuit at an exchange at the distant end of said conductors, armature switches of said operating relays conductively connected to 75 said trunk relays when said selector selects said terminals whereby said trunk relays are rendered directly controllable by said operating relays, a selective switch operable by said trunk relays, and means for restoring 80 said switch responsive to circuit changes produced in said trunk conductors at said selector.

Signed by me at Chicago, Cook County, Illinois, this 11th day of January, 1907.

TALBOT G. MARTIN.
